UNITED STATES PATENT OFFICE

JOHN A. MORROW, OF CHICAGO, ILLINOIS

FREIGHT CAR

Application filed March 3, 1930. Serial No. 432,731.

This invention relates to freight cars and particularly to freight cars of the box or closed type.

One object of the invention is to provide a roof structure for freight cars which may be opened to permit access to the interior of the car from the top for the purpose of conveniently loading and unloading the car.

Another object is to provide a roof structure for cars having a plurality of sections separately mounted to permit opening one or more sections independently of the others.

Another object is to provide a roof structure for cars having a plurality of separately mounted sections so interlocked that the locking of one section will hold all of the sections locked in closed position.

Another object is to provide a sectional roof structure of the character referred to which is comparatively inexpensive to make and install, strong and durable, easy to manipulate, efficient and reliable in use, and protected against leakage of water or the like.

Other objects will be in part obvious and in part pointed out hereinafter.

The invention accordingly consists in the features of construction, combination of elements, and arrangements of parts, which will be exemplified in the structure hereinafter described; and the scope of the application of which will be indicated in the subjoined claims.

In the accompanying drawings in which is shown one of the various possible embodiments of the invention:

Fig. 1 is a top plan view of a box car embodying the invention.

Fig. 2 is a side elevation of the same.

Fig. 3 is an enlarged sectional view taken on the line 3—3 of Fig. 1.

Fig. 4 shows a portion of Fig. 3 with one section of the roof in open position.

Fig. 5 is an enlarged sectional view taken on the line 5—5 of Fig. 1 and showing one section of the roof in open position.

Fig. 6 is an enlarged end view of the car seen from the right in Fig. 1 and showing one section of the roof in open position.

Fig. 7 is an enlarged view of the locking

means taken substantially on the line 7—7 of Fig. 3.

Fig. 8 is a sectional view taken on the line 8—8 of Fig. 3.

Fig. 9 is an enlarged top plan view of a portion of the roof and showing one of the sections in open position.

Referring to Fig. 2, a box car designated 1 is shown, provided with the usual sliding door 2 and the sectional roof to which this application is primarily directed.

As shown in Fig. 1, the roof comprises a plurality of sections, six in the illustrative embodiment, A, B, C, D, E and F, which, when in closed position, interlock to form in effect an integrally tight roof for the car.

Referring to Figs. 3 and 8, each section preferably consists of one or more panels of roofing material, 3 which may be of wood or other suitable material, covered by a waterproof sheet 4, which may be of sheet metal. Supporting ribs 5, preferably of sheet metal, may be secured to the under side of the sections to reinforce them.

The sections E, A and D are separately hinged to a plate 6 secured to one side of the car along its upper edge, and sections F, B and C are similarly hinged to a similar plate 7, similarly secured to the other side of the car.

Plates 6 and 7 are preferably curved as at 8 and the ends of ribs 5, which contact with the curve 8, are similarly curved to facilitate the swinging movement of the sections.

As shown in Figs. 4 and 5, the opening movement of the sections may be limited by a chain or cable 9 secured to the section and the interior of the car side.

To prevent leakage at the meeting edges of the several sections, each section is provided with waterproof edge strips 10, preferably consisting of corrugated plates constructed and arranged to mesh when the several sections are in closed position.

As best shown in Fig. 6, the sections adjacent the car ends may be provided with waterproof strips 11 preferably in the form of sheet metal angle irons bolted to the section and arranged to hang downward outside

95

100

the car end when the section is in closed position.

Sections E, A and D may be provided with a runway 12 to rest on sections F, B and C when the sections are in closed position.

The interlocking arrangement of the several sections is best shown in Figs. 1 and 8. Section A is provided with extension plates 13, preferably of the form shown in Fig. 8, 10 which plates are bolted to section A and extend over and contact with the upper surfaces of sections B, E and D respectively, thus holding said latter sections in closed position. Section B is provided with similar 15 extension plates 13 which extend over and contact with the upper surfaces of sections F and C respectively and hold said sections in closed position. Similar plates 13 may be provided on one or more of sections F, E, C 20 and D. Thus, when all of the sections are closed, and section A is locked, all of the sections will be locked against opening.

Section A may be locked by a spring-pressed latch 14 carried by section A and 25 adapted to snap into a catch 15 carried by section B. As shown in Fig. 7, the latch may be padlocked against opening by a padlock 16 which passes through an eye 17 secured to the latch and an eye 18 firmly secured to the section A.

In operation, section A is first released by removing the padlock 16 and moving the latch 14 out of catch 15 and swinging section A back about its pivotal connection with 35 plate 6. Thereafter one or more of the other sections may be opened as required.

The several sections may be provided with handles 19 preferably sunk in pockets, which handles may be grasped manually or by a 40 hook of a suitable hoist mechanism to swing the sections to open position.

It will be seen that there is provided a construction of an essentially practical nature in which the several objects of the invention are 45 attained.

Among other advantages the invention provides a practical roof structure for freight cars which may be opened for the purpose of 50 conveniently loading and unloading the car. Such an arrangement is particularly advantageous for the loading and unloading of bulky or heavy commodities, as it permits the use of a crane, hoist or lift. It also facilitates the loading of grain, coal or the like 55 through a chute. The several sections being independently mounted may be opened separately, thus facilitating the opening of the car and permitting the car to be opened at 60 one or more points without exposing other portions of the car.

As many other embodiments may be made without departing from the scope of the invention it is to be understood that all matter 65 herein set forth or shown in the accompany-

ing drawings is to be interpreted as illustrative and not in a limiting sense.

I claim:

1. In combination with a box car, a roof comprising a plurality of sections, means for mounting the sections so that they may be swung to open and closed positions, means interlocking the sections in closed position so that the locking of one section will hold all of the sections locked against opening, means for limiting the swinging movement of the sections, and overlapping corrugated strips secured to the sections and bridging the joints therebetween. 70

2. In combination with a box car, a roof comprising a plurality of sections, means for mounting each section so that it may be swung to open and closed positions, means interlocking all of the sections in closed position so that the locking of one section will hold all of the sections against opening, means for limiting the swinging movement of the sections, and weather-proof strips bridging the joints between sections. 80

3. In combination with a box car, a roof comprising a plurality of sections, means for mounting each section so that it may be swung to open and closed positions, means for limiting the swinging movement of the sections, means for locking the sections in closed position, and weather-proof strips secured to the sections and bridging the joints therebetween. 85

4. In combination with a box car, a roof comprising a plurality of separate sections pivoted to each side of the car and adapted to be swung to open and closed positions, and means interlocking the sections in closed position so that the locking of one section will hold all of the sections locked against opening. 100

In testimony whereof, I have signed my name to this specification this 12th day of February, 1930.

JOHN A. MORROW.
